UNITED STATES PATENT OFFICE.

PAUL J. SIMMEN, OF EDEN, NEW YORK.

AUTOMATIC TRAIN CONTROL.

Application filed April 10, 1923. Serial No. 631,098.

This invention relates to railway train control particularly to systems in which there is a combined automatic and manual control and more especially to those in which the movement of trains are indicated and recorded at a central station.

In a companion application filed April 10, 1923, Serial No. 631,097, I have shown a system of signalling in which six fixed signals along the track are controlled from the central office, certain of the signals being also controlled by a track circuit, while others are controlled from the central office.

The object of this invention is to provide a central control signal system by which an operator at a dispatcher's office, interlocking tower, or way station can display six signals to a train, some of the signals being used for safety purposes and others for facility purposes, and in which the safety signals are also automatically controlled by a track circuit, while the facility signals are independent of such track circuit control.

In this invention the signals are preferably cab signals, and means are also shown whereby both cab signals and fixed signals are displayed to trains.

A further object of the invention is to record the movement of trains so that a dispatcher or other officer may intelligently display the proper signal.

Other objects and advantages will appear as the description of the invention progresses and the novel features will be particularly pointed out in the appended claims.

In describing the invention in detail, reference is had to the accompanying drawings wherein I have illustrated a preferred physical embodiment of my invention and wherein like characters of reference designate corresponding parts through the several views and in which:

Figure 1 is a schematic representation of the apparatus and circuits in the dispatcher's office and along the track; Fig. 2, is a schematic representation of the apparatus and circuits on the locomotive or car; Fig. 3, is a modification of Fig. 1, in which the apparatus and circuits along the track are shown for the purpose of controlling both the cab signals and the fixed signals.

Fig. 1 shows a track consisting of track rails 1 and 2. Rail 1 is electrically continuous and rail 2 is divided into sections by means of insulating joints, as 3, thus divid-

ing the track into blocks. Near one end of each block is a track battery as 4, and near the other end of each block is a track relay, as 5, constituting, with their connections to the rails, a track circuit well known to those skilled in the art. Track relay 5 controls two armatures as 6 and 7. When track relay 5 is energized, armature 6 makes contact with front contact 8 and when track relay 5 is deenergized, armature 7 makes contact with back contact 9.

In Fig. 1 are shown an alternating current relay as 10 and a polarized relay as 11, which are located along the track suitably housed. Relay 10 controls an armature as 12, and relay 11 controls two neutral armatures as 13 and 14 and a polarized armature as 15. Along the track are located train control rails as 16 and 17, train control rail 16 being the home train control rail and positioned near the beginning of a new block and train control rail 17 being the distant train control rail, located approximately the breaking distance from the entrance to a new block. Depending upon the several positions of the armatures of relays 10 and 11 six different electrical conditions may be established in train control rails 16 and 17.

Relays 10 and 11 are electrically controlled by two manually operable switches 18 and 19. When switch 18 is in the right hand position thus contacting with spring contact 25, an electrical connection is made to direct current source as 20. When switch 18 is in left hand position connecting with spring contact 46, an electrical connection is made with direct current source 43. When switch 19 is in contact with spring contact 55, an electrical connection is made with alternating current source 51. Electrical sources 20, 43 and 51 are preferably located in the dispatcher's office. Depending upon the several positions of the switches 18 and 19, relays 10 and 11 along the track may be energized or deenergized through three different circuits: The positive direct current circuit; the negative direct current circuit; and the alternating current circuit.

The positive direct current circuit is as follows: from positive pole of battery 20 in the dispatcher's office, wire 21, impedance coil 22, bus 23, wire 24, spring contact 25, switch 18, relay 26, wire 27, impedance coil 28, line wire 29, terminal 30, wire 31, resistance 32, wire 33, terminal 34, wire 35, terminal 36, wire 37, polarized relay 11, wire 38,

impedance coil 39, and wire 40 to track rail 1 and thence by wires 41 and 42 to negative pole of battery 20.

The negative direct current circuit is as follows: from positive pole of battery 43, wires 44, 45 and 41, track rail, wire 40, impedance coil 39, wire 38, polarized relay 11, wire 37, terminal 36, wire 35, terminal 34, wire 33, resistance 32, wire 31, terminal 30, line wire 29, impedance coil 28, wire 27, relay 26, switch 18, spring contact 46, wire 47, bus 48, impedance coil 49, and wire 50 to the negative pole of battery 43.

The alternating current circuit is as follows: from alternating current source 51 in the dispatcher's office, wire 52, condenser 53, bus 54, spring contact 55, switch 19, alternating current relay 56, condenser 57, wire 58, line wire 29, terminal 30, wire 31, resistance 32, wire 33, terminal 34, wire 59, alternating current relay 10, wire 60, condenser 62, wires 63 and 40, track rail 1, and wires 41, 45, and 64 to alternating current source 51.

Impedance coils 22, 49, 28 and 39 are inserted to prevent the flow of alternating current through the circuit in which they are inserted and condensers 53, 57 and 62 are inserted to prevent the flow of direct current through the circuits in which they are inserted. Relays 26 and 56 in the dispatcher's office are for the purpose of recording train movements which will be more fully described hereinafter. Resistance 32 is inserted in the circuit to decrease the flow of current through relays 26 and 56 for a purpose to be explained hereinafter.

By means of the three hereinbefore described circuits referred to hereinafter as the main dispatcher's circuits, which are established through the several positions of the manually operable switches 18 and 19, six different electrical conditions can be established in relays 10 and 11, which result in the armatures of relays 10 and 11 assuming different positions, and by reason of the different positions of armatures of relays 10 and 11, different circuits are established to train control rails 16 and 17 so that the train control rails are charged with electrical energy in six different ways.

The six different electrical conditions of relays 10 and 11 and train control rails 16 and 17 are established as follows:

First condition.—When switch 18 is in contact with spring contact 25 and switch 19 is in contact with spring contact 55, polarized relay 11 is positively energized and alternating current relay 10 is also energized. Train control rails 16 and 17 are also energized with positive direct current and alternating current through certain branch circuits which will be more fully described hereinafter.

Second condition.—When switch 18 is in contact with spring contact 16 and switch 19

is in contact with spring contact 55, polarized relay 11 is negatively energized and alternating current relay 10 is also energized. Train control rails 16 and 17 are also charged with negative direct current and alternating current.

Third condition.—When switch 18 is in contact with spring contact 25 and switch 19 is disconnected from spring contact 55, polarized relay 11 will be positively energized but alternating current relay 10 will be de-energized. Train control rails 16 and 17 will be charged with positive direct current only.

Fourth condition.—When switch 18 is in contact with spring contact 46 and switch 19 is disconnected from spring contact 55, polarized relay 11 will be negatively energized and alternating current relay 10 will be de-energized. Train control rails 16 and 17 will be charged with negative direct current only.

Fifth condition.—When switch 18 is disconnected from both spring contacts 25 and 46 and switch 19 is in contact with spring contact 55, polarized relay 11 will be de-energized and alternating current relay 10 will be energized. Train control rails 16 and 17 will be charged with alternating current only.

Sixth condition.—When switch 18 is disconnected from both spring contacts 25 and 46 and switch 19 is disconnected from spring contact 55, polarized relay 11 and alternating current relay 10 are both de-energized, and train control rails 16 and 17 are also de-energized.

I will now describe the branch circuits through which the train control rails 16 and 17 are electrically conditioned in six different ways as hereinbefore described.

When polarized relay 11 is positively energized and alternating current relay 10 is energized with alternating current, corresponding to the first condition, armatures 13 and 14 of relay 11 will make contact with front contacts 65 and 66 and polarized armature 15 will make contact with contact 67 and armature 12 of relay 10 will make contact with front contact 68. This position of the several armatures establishes a branch circuit from terminal 36 in the main dispatcher's circuit to train control rails 16 and 17 as follows: from terminal 36, wire 69, armature 12 of relay 10, front contact 68, wire 70, armature 13 of relay 11, front contact 65, wire 71, polarized armature 15, contact 67, wire 72, front contact 8, armature 6, of track relay 5, wires 73, and 74 to train control rails 16 and 17. It will thus be seen that when switches 18 and 19 in the dispatcher's office are in the position corresponding to the first condition, train control rails 16 and 17 are charged with positive direct current and alternating current.

When polarized relay 11 is negatively energized and alternating current relay 10 is energized with alternating current, corresponding to the second condition, armatures

- 5 13 and 14 of relay 11 will make contact with front contacts 65 and 66, but polarized armature 15 will now be in the left hand position and will make contact with contact 75. Armature 12 of relay 10 will make contact with 70
 10 front contact 68. This position of the several armatures, establishes a branch circuit from terminal 36 in the main dispatcher's office to train control rails 16 and 17 as follows: from terminal 36, wire 69, armature 15, contact 75, wires 76, 77 and 74 to train 75
 15 control rails 16 and 17. Under these conditions train control rails 16 and 17 are 80
 20 charged with negative direct current and alternating current.

When polarized relay 11 is positively energized and alternating current relay 10 is deenergized, corresponding to the third condition, armatures 13 and 14 of relay 11 will make contact with front contact 65 and 66 and polarized armature 15 will be in the right hand position and make contact with contact 67. Armature 12 of relay 10, since 90
 25 relay 10 is now deenergized, will make contact with back contact 78. This position of the several armatures establishes a branch circuit from terminal 36 in the main dispatcher's circuit to train control rails 16 and 17 as follows: from terminal 36, wire 69, armature 12, back contact 78, wire 79, armature 14, front contact 66, wires 88, 77, and 74 to the train control rails 16 and 17. Under 95
 30 these conditions train control rails 16 and 17 are charged with positive direct current only, since switch 19 in the dispatcher's office, is open.

When polarized relay 11 is negatively energized and alternating current relay 10 is deenergized, corresponding to the fourth condition, armatures 13 and 14 of relay 11 will make contact with front contact 65 and 66 and polarized armatures 15 will be in the left hand position and make contact with contact 75. Armature 12 of relay 10 will make contact with back contacts 78. This position of the several armatures establishes a branch circuit from terminal 36 in the main dispatcher's circuit to train control 100
 40 rails 16 and 17 as follows: from terminal 36, wire 69, armature 12, back contact 78, wire 79, armature 14, front contact 66, and wires 88, 77 and 74 to train control rails 16 and 17. Under 105
 45 these conditions train control rails 16 and 17 are charged with negative direct current only.

When polarized relay 11 is deenergized and alternating current relay 10 is energized, corresponding to the fifth condition, armatures 13 and 14 of relay 11 will drop away 110

and armature 13 will make contact with back contact 89. Armature 12 of relay 10 will make contact with front contact 68. This position of the several armatures establishes a branch circuit from terminal 36 in the main dispatcher's circuit to train control rails 16 and 17 as follows: from terminal 36, wire 69, armature 12, front contact 68, wire 70, armature 13, back contact 89, and wires 88, 77 and 74 to train control rails 16 and 17. Under 115
 50 these conditions train control rails 16 and 17 are charged with alternating current only.

When polarized relay 11 and alternating current relay 10 are both deenergized, corresponding to the sixth condition, train control rails 16 and 17 are also deenergized 80
 55 since both switches 18 and 19 in the dispatcher's office are open.

It will thus be seen that the dispatcher 85 may electrically condition train control rails 16 and 17 to any one of the six hereinbefore described conditions; the system preferably is so arranged however, that the first condition when the train control rails 16 and 17 90 are charged with positive direct current and alternating current, is also subject to the control by a track circuit, thus when the dispatcher has placed the switches 18 and 19 to correspond to this condition, and there is a 95 train in the block ahead, track relay 5 will become deenergized in a manner well known to those skilled in the art, and armature 6 will drop and break front contact 8. When this occurs no energy can reach train control 100 rails 16 and 17 and therefore they become deenergized, resulting in the sixth condition.

Since only the branch circuit resulting from the first condition is taken through the armatures of track relay 5, electrical conditions Nos. 2, 3, 4 and 5 are independent of such track circuit control and the train control rails 16 and 17 will be charged as intended by the dispatcher whether there is a train in the block or not. It will be obvious 110 however to those skilled in the art that any one of the other branch circuits corresponding to any of the other electrical conditions may be taken through track relay 5 in a similar manner, thus making the circuit representing any particular condition also subject to track circuit control.

I will now describe the apparatus and circuits on the locomotive or car capable of being conditioned in six different ways corresponding to the six different electrical conditions of train control rails 16 and 17. These are shown in Fig. 2 and are similar to the apparatus and circuits shown in my prior Patent No. 1,399,027, granted December 6, 1921. 120 The instrumentalities corresponding to the electrical conditions of the train control rail are designated by A, B, C, D, E, F. While these instrumentalities in Fig. 2 are shown as lamps, they may equally as well represent 125
 60 65 70 75 80 85 90 95 100 105 110 115 120 125 130

an electro-magnetic device to which motion is given depending upon whether the circuit is energized or deenergized and such electro-magnetic devices may be used for other purposes than, or in addition to, the display of signals to the engineer; such as is well known to those skilled in the art, the proper control of speed control devices or air valves or both.

10 In Fig. 2 is shown an electrical contact shoe as 90, so positioned on the locomotive so as to make contact with train control rails 16 and 17. The contact shoe is hinged as at 91. Train control rails 16 and 17 are inclined at the ends so as to form a ramp in the usual manner, as shown in my prior Patent No. 1,140,623, granted May 25, 1915, and when the contact shoe slides along this ramp, the shoe is tilted so as to break the contacts, 15 as 92, 93 and 94. This motion of the shoe compresses spring as 95. When the contact shoe leaves the other end of train control rail, spring 95 forces contact shoe to the normal position, again making contact with 20 92, 93 and 94. A metallic plate as 96 fixed to the contact shoe 90, but insulated therefrom, is so positioned as to make contact with contacts 93 and 94.

The locomotive also carries a polarized relay as 97 and an alternating current relay as 98, with its companion direct current winding as 99, the battery as 100, and another battery as 101. Polarized relay 97 controls the position of neutral armatures 30 102, 103 and 104 and polarized armatures 105, 106 and 107 and 108. Polarized armatures 107 and 108 are pole changing members of a switch for the purpose of changing the polarity of current from battery 100. 35 Alternating current relay 98 and its companion direct current coil 99 control the position of armatures 109 and 110.

40 Impedance coil as 111 is inserted to prevent the flow of alternating current in the circuit in which it is inserted, and condenser as 112 is inserted to prevent the flow of direct current in the circuit in which it is inserted.

45 Armature 102 of relay 97 controls a stick circuit for relay 97 which will be described hereinafter and armature 109 of track relay 98 controls another stick circuit through coil 99 which will also be described hereinafter.

50 I will now describe the operation of signals on the locomotive in response to the six electrical conditions of the train control rails as hereinbefore described.

55 *First condition.*—When the contact shoe 90 is passing a train control rail which is energized with positive direct current and alternating current, direct current will flow to shoe 90, wires 113 and 114, impedance coil 111, wire 115, polarized relay 97, wires 116, 117, 118 and 119, axle 120, wheel 121, to track rail 1 and thence the circuit is completed

through the main dispatcher's circuit and branch circuit hereinbefore described. Alternating current will also flow to train control rail 16 as follows: contact shoe 90, wires 113 and 122, condenser 112, wire 123, alternating current relay 98, wires 124, 117, 118 and 119, axle 120, wheel 121, to track rail 1 and thence the circuit is completed through the main dispatcher's circuit and branch circuits hereinbefore described. This will 75 result in armatures 102, 103 and 104 of relay 97 making contact with front contacts 125, 126 and 127 and polarized armatures of relay 97 will be placed in the right hand position as shown in Fig. 2, thus making 80 contact with their respective contacts 128, 129, 130 and 131. Armature 109 and 110 of relay 98 will make contact with front contact 132 and 133. In this position of the several 85 armatures, a circuit is established through signal A as follows: from positive pole of battery 100, wires 134 and 135, contact 130, polarized armature 107, wire 136, armature 110, front contact 133, wire 137, armature 103, front contact 126, wire 138, polarized 90 armature 105, contact 128, wire 139, signal A, wires 140, 118 and 141, polarized armature 108, contact 131, and wire 142, to negative pole of battery 100.

95 As the contact shoe 90 leaves the other end of train control rail, the armature of relays 97 and 98 are maintained in the same position after the electromotive forces from the dispatcher's office ceases to influence them through the following two stick circuits: as the contact shoe 90 leaves the train control rail, spring 95 closes contacts 92, 93 and 94 and a stick circuit is established through polarized relay 97 as follows: from positive pole of battery 100, wires 134 and 135, contact 130, polarized armature 107, wire 143, armature 102, front contact 125, wire 144, contact 92, shoe 90, wires 113 and 114, impedance coil 111, wire 115, polarized relay 97, wires 116, 117 and 110 141, polarized armature 108, contact 131, and wire 142 to negative pole of battery 100. The second stick circuit is established through coil 99 of relay 98 as follows: from battery 101, wire 145, coil 99, wire 146, contact 94, metallic plate 96, contact 93, wire 147, front contact 132, armature 109, wire 148, to battery 101. Thus the armatures are maintained in the same position and signal A is continued until the next train 115 control rail is encountered.

120 *Second condition.*—When the contact shoe 90 is passing a train control rail which is energized with negative direct current and alternating current, direct current will 125 flow from track rail 1, wheel 121, axle 120, wires 119, 118, 117 and 116, polarized relay 97, wire 115, impedance coil 111, wires 114 and 113, contact shoe 90, to train control rail 16, and thence the circuit is completed 130

through the main dispatcher's circuit and second stick circuit however, while it is now closed at contacts 93 and 94, the front contact 132 is now open and alternating current relay 98 and coil 99 will continue to be deenergized. Thus signal C will be continued until the next train control rail is encountered.

5 through the main dispatcher's circuit and second stick circuit however, while it is now closed at contacts 93 and 94, the front contact 132 is now open and alternating current relay 98 and coil 99 will continue to be deenergized. Thus signal C will be continued until the next train control rail is encountered.

6 Polarized relay 97 will now be negatively energized, armatures 102, 103 and 104 still make contact with front contacts 125, 126 and 127 but polarized armatures 105, 106, 107 and 108 assume the left hand position, opposite to that as shown in Fig. 2 and they make contact with their respective contacts 10 as 149, 150, 151 and 152. Alternating current will also flow through relay 98 as described in the first condition and armatures 109 and 110 still make contact with front contacts 132 and 133. In this position of the several armatures, a circuit is established through signal B as follows: from positive pole of battery 100, wires 134, 153, contact 152, polarized armature 108, wires 141, 118 and 140, signal B, wire 154, contact 149, polarized armature 105, wire 138, front contact 103, wire 137, front contact 133, armature 110, wire 136, polarized armature 107, contact 151, and wire 142 to negative pole of battery 100.

15 20 25 As the contact shoe leaves the other end of the train control rail, the stick circuit through relay 97 is again established as follows: from the positive pole of battery 100, wires 134 and 153, contact 152, polarized armature 108, wires 141, and 117 and 116, polarized relay 97, wire 115, impedance coil 111, wires 114, and 113 contact shoe 90, contact 92, wire 144, front contact 125, armature 102, wire 143, polarized armature 107, contact 151, and wire 142 to the negative pole of battery 100. The second stick circuit through coil 99 of relay 98 is also re-established as hereinbefore described. Thus signal B is continued until the next train control rail is encountered.

30 35 40 45 50 55 60 65

Fourth condition.—When the contact shoe 90 is passing a train control rail which is energized with negative direct current only, polarized relay 97 will be negatively energized and the position of its armatures will be as described in the second condition. Alternating current relay 98 will be de-energized and armature 110 will make contact with back contact 155. In this position of the several armatures, a circuit is established through signal D as follows: from positive pole of battery 100, wires 134 and 153, contact 152, polarized armature 108, wires 141, 118 and 140, signal D, wire 159, contact 150, polarized armature 106, wire 157, front contact 127, armature 104, wire 156, back contact 155, armature 110, wire 136 polarized armature 107, contact 151, and wire 142 to the negative pole of battery 100.

70 75 80 85 90 95 100 As the contact shoe leaves the other end of the train control rail, the stick circuit through relay 97 is reestablished as described in the second condition. The second stick circuit through relay 98 and coil 99 is still inoperative however, as described in the third condition. Thus signal D is continued until the next train control rail is encountered.

Fifth condition.—When the contact shoe 90 is passing a train control rail which is energized with alternating current only, no current will flow through relay 97 and its neutral armatures 102 and 103 and 104 will drop and armatures 103 and 104 will close back contacts 160 and 161. Alternating current relay 98, however, will be energized as hereinbefore described in the first condition and its armatures 109 and 110 will make contact with front contacts 132 and 133. In this position of the several armatures a circuit is closed through signal E as follows: from positive pole of battery 100, wires 134 and 135, contact 130, polarized armature 107, wire 136, armature 110, front contact 133, wire 137, armature 103, back contact 160, wire 162, signal E, wires 140, 118 and 141, polarized armature 108, contact 131, and wire 142, to the negative pole of battery 100.

110 115 120 125 130 As the contact shoe 90 leaves the other end of the train control rail, the stick circuit through relay 97 is inoperative. While contact 92 is now closed, the stick circuit is now open at front contact 125. The second stick circuit through coil 99 is now operative, however, as described in the first condition, thus signal E is continued until the next train control rail is encountered.

Sixth condition.—When the contact shoe 130

As the contact shoe 90 leaves the other end of train control rail, the stick circuit through relay 97 is reestablished as hereinbefore described in the first condition. The

90 is passing a train control rail which is de-energized, both relays 97 and 98 will become deenergized since the two stick circuits are now open at contacts 92, 93 and 94. Armatures 102, 103 and 104 of relay 97 will drop away and armatures 103 and 104 will make contact with back contacts 160 and 161. Armature 110 of relay 98 will make contact with back contact 155. In this position of the several armatures a circuit is closed through signal F as follows: from positive pole of battery 100, wires 134 and 135, contact 130, polarized armature 107, wire 136, armature 110, back contact 155, wire 156, armature 104, back contact 161, wire 163, signal F, wires 140, 118 and 141, polarized armature 108, contact 131, and wire 142 to the negative pole of battery 100.

As the contact shoe 90 leaves the other end of the train control rail, both stick circuits are now inoperative since the stick circuit through relay 97 is now open at front contact 125, and the stick circuit through coil 99, is now open at front contact 132. Thus signal F is continued until an energized train control rail is reached.

It will thus be seen that under any of the six electrical conditions of the train control rails, one of the six signals on the locomotive is established, when a locomotive passes a train control rail and the particular signal established at the rail is continued on the locomotive until the next train control rail is encountered.

35 While the dispatcher is thus able by placing switches 18 and 19 in the dispatcher's office in the several positions described, to display six different signals on the locomotive, signal A is annulled or made inoperative and signal F will be displayed, if there is a train in the block ahead, by reason of the branch circuit which electrically conditions train control rails 16 and 17 in accordance with the first condition, being taken through track relay 5, as hereinbefore described. Signals B, C, D, E and F, however, will be displayed on the locomotive irrespective of whether there is a train in the block ahead or not.

50 I will now describe the recording apparatus in the dispatcher's office for recording the progress of trains over the division. A record sheet as 164 is suitably mounted and driven by a roller as 165, which in turn is driven by a shaft as 166. Shaft 166 receives motion through a ratchet wheel 167. A pawl as 168, is pivotally connected to armatures 169 of an electromagnet as 170. Armature 169 is hinged at 171. When electromagnet 170 is periodically energized, motion is given to ratchet wheel 167 through pawl 168. A spring as 172 normally pulls armature 169 and pawl 168 to the right when electromagnet 170, is not energized.

55 Electromagnet 170 is connected by a wire

173 to a make-and-break device as 174, which make-and-break device is periodically operated by clock as 175. This may well be of the form as shown in my prior Patent No. 1,203,146, granted October 21, 1916. When the make-and-break device 174 is closed, the electromagnet 170 is energized through the following circuit: from battery 176, wire 177, electromagnet 170, wire 173, make-and-break device 174 is operated, say every five seconds, by the clock 175, so as to give a slow and uniform movement to the record sheet 164 through ratchet wheel 167 and pawl 198.

The record sheet 164 is transversely divided into sections as 180 and 181, each section representing a block along the track. Longitudinally the record sheet is divided into time lines such as 1.00 a. m., each one of the lines representing a one-minute interval. Since the make-and-break device 174 is operated intermittently continuously, it will be seen that longitudinally the record sheet assumes a constantly changing position during the 24 hours of the day.

Adjacent to the record sheet 164 are perforating magnets as 182 and 183 for each space representing a block on the record sheet. Pivotally attached to armature 184 of these perforating magnets are perforating needles as 185, so positioned adjacent to the record sheet that when a perforating magnet is energized, a perforation is made upon the record sheet. The circuit through perforating magnet 182 is controlled by armatures 186 of relay 26, and the circuit through perforating magnet 183 is controlled by armature 187 of alternating current relay 56.

When switch 18 is in contact with either spring contact 25 and 46 and there is no train in the block ahead, current is flowing through relay 26, but this current is not sufficient, by reason of resistance 32 in the main circuit, to attract armature 186 so as to close front contact 188, and therefore the circuit through perforating magnet 182 is not closed. If however, there is a train on the block track relay 5 becomes deenergized and armature 7 of track relay 5, establishes a shunt circuit which cuts out resistance 32, as follows: from terminal 30 in the main dispatcher's circuit wire 189, armature 7, back contact 9, wire 190, and wire 40 to track rail. With resistance 32 thus cut out of the circuit there is now sufficient current flowing through relay 26, to attract its armature 186 and close front contact 188. When this occurs a circuit is closed through perforating magnet 182 as follows: from battery 176, wire 191, metallic contact plate 192, bus 193, wire 194, perforating magnet 182, wire 195, front contact 188, armature 186, wire 196, bus 197, and wire 179 to the other side of battery 176.

Similarly when switch 19 is in contact with spring contact 55 and there is no train in the block, current is flowing through relay 56, but this current is not sufficient by reason of the resistance 32 in the main dispatcher's circuit to attract armature 187, so as to close front contact 198, and therefore, a circuit through perforating magnet 183 is not closed. If, however, there is a train 10 in the block, track relay 5 becomes deenergized and armature 7 of track relay 5 establishes the same shunt circuit as hereinbefore described, thus cutting out resistance 32. With resistance 32 thus cut out of the circuit, there is sufficient current flowing through relay 56 to attract the armature 187 and close front contact 198. When this occurs a circuit is closed through perforating magnet 183, as follows: from battery 20 176, wire 191, metallic contact plate 192, bus 193, wire 194, perforating magnet 183, wire 199, front contact 198, armature 187, wire 200, bus 197, and wire 179, to the other side of battery 176.

25 It will thus be seen that when switch 18 is in contact with either spring contacts 25 or 46 and there is a train in the block, perforating magnet 182 will make a perforation on the record sheet and when switch 19 30 is in contact with spring contact 55, and there is a train in the block, perforating magnet 183 will make a perforation on the record sheet.

35 The circuits through perforating magnets 182 and 183 are taken through a circuit-breaking device 192 and these circuits are periodically made and broken. This circuit breaking device operates as follows: metallic contact plate 192, is attached to armature 169 and insulated therefrom and every time the electromagnet 170 is energized, which as hereinbefore stated is say every five 40 seconds, the contacts through wire 191 and bus 193 are closed through the metallic plate 192. When magnet 170 is deenergized, armature 169 is pulled to the right by spring 172 and the circuit through wire 191 and bus 193 is broken. By reason of this periodic 45 breaking of the circuit through perforating magnets 182 and 183 a continuous perforation is made on the record sheet as long as the block is occupied. It will thus be seen that when a train enters a block and either switches 18 or 19 is closed either perforating magnet 182 or 183 commences to perforate, thus recording the exact time when a 50 train enters a block and the perforating magnet continues to perforate until the train has left the block; thus recording the length of time the train remained in the block.

55 The purpose of the invention is first of all to provide instrumentalities or signals to make the operation of trains safe, but in addition to also provide instrumentalities or signals, which will enable the dispatcher to

facilitate the movement of trains. For instance signal A and signal F may be used for safety purposes, signal A indicating a clear track ahead and signal F indicating danger or stop. The other signals may be used for 70 facility purposes, such as indicating to the engineer to stop at the next siding and remain on the main track, or to stop at the next siding and pull into the siding, or to stop at the next siding and report to the dispatcher or advise the engineer to listen in on the wireless telephone or any of the signals 75 may be used as designated by the executive officers of the railway, or some of the signals, particularly those for safety purposes, may 80 be automatically controlled by a track circuit in addition to the dispatcher's control, while others of the signals particularly those used for facility purposes, may be independent of track circuit control, but only subject to the 85 dispatcher's control.

Fig. 3, shows a modification of the track layout of Fig. 1. Under some circumstances it may be desirable to display fixed signals which are located along the trackway to the 90 engineer, in addition to the cab signals as heretofore described. Fig. 3 shows how this may be accomplished. Alternating current relay 10 in Fig. 3 performs the same function as alternating current relay 10 in Fig. 1, 95 and armature 12 of relay 10 functions the same as armature 12 in Fig. 1. Polarized relay 11 in Fig. 3 performs the same functions as polarized relay 11 in Fig. 1, and its neutral armatures 13 and 14 function the 100 same way as in Fig. 1. Polarized armature 15 of relay 11 functions the same way as armature 15 of relay 11 in Fig. 1. Thus train control rails 16 and 17 may be electrically conditioned to give the six different 105 conditions as in Fig. 1. The six fixed signals along the track are designed as Nos. 1, 2, 3, 4, 5 and 6 and a seventh signal is also shown designated as No. 7. These seven signals are controlled in the identical manner as described and as shown in Fig. 2, in my above mentioned co-pending application Serial No. 631,097. The only additional parts added to Fig. 3 in this application are additional armatures under control of relays 10 and 11 110 and these additional armatures control the several circuits through the six fixed signals as shown and described in my co-pending application Serial No. 618,193, filed February 10, 1923. Those skilled in the art will 115 readily understand the operation and circuits as shown in Fig. 3 by combining the apparatus and circuits in Fig. 1 of this invention and the apparatus and circuits of Fig. 2 of my said co-pending application, 120 Serial No. 631,097.

125 Although I have particularly described and illustrated one preferred physical embodiment of my invention and explained the principle and construction thereof, nevertheless,

less, I desire to have it understood that the form selected is merely illustrative, and does not exhaust the possible physical embodiment of means underlying my invention.

- 5 6. What I claim as new and desire to secure by Letters Patent of the United States, is:
1. In a railway control system, in combination: a trackway; means dividing the trackway into electrically isolated sections; 10 train control rails positioned at intervals along the trackway; a car movable upon the trackway; means for train control positioned on the car; a central station; a plurality of sources of current at the central station; a 15 plurality of relays associated with each section and means connecting the central station and the relays whereby a selective energization of the relays is had; means connecting the relays and the train control rails 20 and the sources of current whereby a selective energization of the train control rails is had whereby the means on the car is selectively affected; and a track relay, the armature of which controls one, without controlling 25 the others, of the permissible energizations of the train control rails as provided for at said central station.
  2. In a railway train control system, in combination: a trackway; means dividing 20 the trackway into electrically isolated sections; train control rails positioned at intervals along the trackway; a car movable upon the trackway; a group of more than two signals on the car severally responsive to different electrical conditions of said train 25 control rails; a central station; means at said central station operative in combination

with sources of current for selectively establishing different electrical conditions of the train control rails to which said signals are 40 characteristically responsive, energized conditions of the train control rails being effected by branch circuits; and a track relay by which at least one of said branch circuits is automatically controlled, the remaining 45 branch circuits not being subject to control by said track relay.

3. In a railway train control system, in combination: a trackway; means dividing the trackway into electrically isolated sections; train control rails positioned at intervals along the trackway; a car movable upon the trackway; a group of more than two signals on the car severally responsive to different electrical conditions of said train 50 control rails; a central station; means at said central station operative in combination with sources of current for selectively establishing different electrical conditions of the train control rails to which said signals are 55 characteristically responsive, energized conditions of the train control rails being effected by branch circuits; and a track relay by which at least one of said branch circuits is automatically controlled, said relay being 60 operative when its corresponding section is occupied by a car to break said branch circuit and alter the signal aspect of said group from that provided for by the completion of said branch circuit, the other 70 branch circuits not being subject to control by said relay.

PAUL J. SIMMEN.
